UNITED STATES PATENT OFFICE.

CARL H. BISSELL AND ELDA G. SMITH, OF SYRACUSE, NEW YORK, ASSIGNEES TO
CROUSE-HINDS COMPANY, OF SYRACUSE, NEW YORK, A CORPORATION OF NEW
YORK.

ELECTRICAL APPLIANCE.

1,265,294.

Specification of Letters Patent.

Patented May 7, 1918.

Original application filed August 7, 1914, Serial No. 855,546, Patent No. 1,227,241. Divided and this application
filed May 4, 1917. Serial No. 166,301.

To all whom it may concern:

Be it known that we, CARL H. BISSELL and
ELDA G. SMITH, citizens of the United
States, and residents of Syracuse, in the
5 county of Onondaga and State of New York,
have invented a certain new and useful
Electrical Appliance, of which the following
is a specification.

This invention has for its object an elec-
10 trical appliance, particularly adapted for
storage battery charging stations in railroad
terminals and coach yards; and it consists
in the novel combinations and constructions
hereinafter set forth and claimed.

15 In describing this invention, reference is
had to the accompanying drawings, in which
like characters designate corresponding
parts in all the views.

Figures 1 and 2 are sectional views, partly
20 in elevation, of this appliance, an extension
base being shown in Fig. 1, and omitted in
Fig. 2.

Fig. 3 is a plan view of the appliance, the
upper section of the housing being removed.

25 This appliance comprises a receptacle, a
support therefor, and a housing including
an upper section and two lower sections or
bases upon which the support for the recep-
30 tacle and the upper section of the housing
are interchangeably mounted, one of the
lower sections having a cap piece associated
therewith, which is interchangeably mount-
able with the upper section on the other base
35 section of the housing.

1 and 2 are receptacles or sockets mounted
upon a support, as a plate 3, diagonally op-
posite each other and with their entrances
facing laterally in opposite directions, each
socket having binding devices 4, 5 at their
40 rear-ends for connection to electric wires,
the binding devices being mounted on the
terminal pieces 6, 7 of the sockets and the
binding devices of each socket being located
at the side of the other socket.

45 As here shown, the plate 3 is square and
the rear ends of the receptacles or sockets
overlap each other as seen in Fig. 3. The
plate 3 is also formed with suitable insu-
50 lated wire openings 8 located in the rear of
the receptacles 1, 2 nearly beneath the bind-
ing devices, the wire openings communicat-
ing with the base or lower section of the
housing upon which the plate 3 is mounted.

Each receptacle is connected to the plate 3
in any suitable manner, as by screw bolts 9. 55

10 is the main base or lower section of the
housing, and 11 is a supplemental or exten-
sion base or lower section upon which the
plate 3 may be interchangeably mounted. 12
is the upper section of the housing which is 60

interchangeably mountable upon either the
bases 10 or 11.

The main base 10 is a conduit outlet box
having internally threaded nipples 13 for
connection with electrical conduits, an open- 65
ing 14 at its upper side, an upwardly ex-
tending flange 15 skirted the opening, and
a bearing face 16 around the flange. The ex-
tension base or lower section of the housing
is carried at the upper end of a pipe or con- 70
duit 17, the lower end of which is connected
to a cap piece 18 interchangeably mountable
with the upper section 12 of the housing on
the open side of the base 10. The pipe 17
screws at its opposite ends into internally 75
threaded nipples 19, 20 provided on the base
11 and cap 18.

The extension base 11 is formed with an
opening 14* skirted by a flange 15*, which
flange is surrounded by a bearing face 16*, 80
all similar to the opening, flange and bear-
ing face 14, 15, 16 of the main base 10. The
plate or support 3 may be secured to either
of the bases 10, 11 by screws 21 extending
through openings in the plate 3 and thread- 85
ing into lugs 21* or 21* in the base 10 or 11,
the plate 3 resting upon the edge of the
flange 15 or 15*.

The upper section of the housing which is
interchangeably mountable upon either of 90
the bases 10, 11, is formed with a flange 22
complemental to the bearing face 16 or 16*
and is attachable to either of said bases by
screws 23 extending through threaded open-
ings in the flange and in the bearing face 16, 95
a gasket 24 being usually interposed between
the flange and the bearing face. The cap
piece 18 is also formed with a bearing face
25 complementary to the bearing face 16.

The section 12 of the housing is formed 100
with a wall 26 which skirts the sides of the
receptacles 1, 2 and which is provided with
the flange 22 at its lower margin, this wall
26 having openings 27 aligned with the en-
trances of the receptacles or sockets 1, 2. 105
28 are spring pressed hinged covers for

the openings 27, said covers being hinged to leaves 29 projecting upwardly from the wall 26 and top of the section 12, the hinge leaves 29 being shaped to house the springs 30 surrounding the hinge pins.

31 is a plug movable into either one of the sockets 1, 2, and 32 are eyebolts hinged to the section 12 and movable into open-ended slots or notches 33 provided in lugs 34 on opposite sides of each plug 31; and 35 are wing nuts screwing on the eyebolts against the lugs 34 for holding the plug 31 from withdrawal. The eyebolts are mounted on pins 36 which are supported by lugs 37, 38 projecting from the wall 26 of the housing section 12.

In use, the base section 10 may be mounted upon the surface of the ground, and in such case the supporting plate 3 for the receptacles 1, 2 and the upper section 12 of the housing are mounted directly upon the base 12, as seen in Fig. 2. But in case of underground wiring, the base 10 is located below the surface of the ground, the cap piece 18 mounted thereon and the supporting plate 3 for the sockets 1, 2 and the upper section 12 of the casing are mounted upon the extension base 11, carried at the upper end of the pipe 17, the lower end of which is mounted in the cap piece 18. Hence, the housing section 12 and the socket or receptacle supporting plate 3, by means of our invention, can be used interchangeably for surface wiring or for underground wiring.

In use, the appliance is mounted at one side of a car track or between double tracks, as will be understood by those skilled in the art, and a plug 31 is attached to one end of a wire cord, the other end of which is attached to a plug which fits a socket on the car, which socket is connected to the storage battery.

This invention is particularly advantageous in that owing to the arrangement of the receptacles or sockets 1, 2, and other wire connections, a particularly compact appliance is provided, and further in that owing to the fact that the support for the receptacles and the upper section of the housing are interchangeably mountable upon two bases, the appliance is readily adapted for surface or underground wiring.

The arrangement of the sockets 1, 2 and contiguous parts on the base plate and the cover 12 with the doors thereon for opening and closing the sockets, forms the subject-matter of our application, Sr. No. 855,546, filed August 7, 1914, matured into Patent

No. 1,227,241, May 22, 1917, of which this is a division.

60

What we claim is:

1. An electrical appliance comprising an electrical receptacle, a support therefor, and a housing including an upper section and two lower sections or bases upon which the support and the upper section are interchangeably mountable, and a cap piece connected to one of the lower sections or bases, which cap piece is interchangeably mountable with the upper section on the other base, substantially as and for the purpose set forth.

2. An electrical appliance comprising an electrical receptacle, a support therefor, and a housing including an upper section, and two lower sections or bases, each base having an opening in one side and a bearing face around the opening, and the support being interchangeably mountable on the open side of either base, and the upper section 80 having a circumferential bearing face complementary to the bearing face of either base, substantially as and for the purpose described.

3. An electrical appliance comprising an electrical receptacle, a support therefor, and a housing including an upper section and two lower sections or bases, each base having an opening in one side and a bearing face around the opening, and the support 90 being interchangeably mountable on the open side of either base, and the upper section having a circumferential bearing face complementary to the bearing face of either base, and a cap piece connected to one of the lower sections or bases, the cap piece 95 having a bearing face complementary to the bearing face of the other base, substantially as and for the purpose specified.

4. An electrical appliance comprising an electrical receptacle, a support therefor, and a housing including an upper section, a main base and an extension base, the support and the upper section being interchangeably mountable with the extension 105 base on the main base, and the support and the upper section being mountable on either the extension base or the main base, substantially as and for the purpose set forth.

In testimony whereof, we have hereunto signed our names at Syracuse, in the county of Onondaga, and State of New York, this 27th day of April, 1917.

CARL H. BISSELL.
ELDA G. SMITH.
